THERMOSTATIC LOCKING DEVICE

Heinz Schirokauer, Stockholm, Sweden, assignor
to Gunnar Mannheimer, Skuruborg, Ektorp,
Sweden

Application October 20, 1938, Serial No. 235,992
In Sweden January 15, 1938

9 Claims. (Cl. 200—116)

The present invention relates to a locking device for the temporary inter-locking of two parts being normally movable in relation to one another in a certain direction of operation. The mutually movable parts are associated with a number of abutments, staggered in the direction of operation and cooperating with a locking member, adapted to perform a reciprocating movement under the control of a thermostat so as to engage said abutments in timed order of sequence and release the parts from one another in a stepwise fashion. The invention will find its application, *inter alia*, in automatic switches for staircase illumination systems in buildings and in all kinds of electric timed switches.

According to the present invention the locking member is adapted to swing about different axes of rotation in its reciprocating shifting movement.

The invention will be explained in detail with reference to the accompanying drawings, further features of the invention being then also mentioned. On the drawings—

Fig. 1 is an embodiment of the invention, viewed in a certain projection, together with an accompanying diagram of connections.

Figs. 2 and 3 show the arrangement according to Fig. 1 viewed from the lines 2—2 and 3—3 respectively.

The Figs. 4 to 6 show different shifting positions of the device. Fig. 5a shows a modification.

According to the drawings a cylindrical standard 2 is mounted on the base plate 1 and a sleeve-shaped push-button 3 is mounted on the top thereof. Under the action of a spring power 4 the button has a tendency to take up the raised position shown on the drawings. The button 3 is provided with two laterally projecting lips 5, 6 which are mutually parallel and spaced apart in a direction perpendicular to the direction of operation of the button. Their shape is visible more clearly in Fig. 3. According to the figure the two lips are provided with step-wise contours the steps of which are staggered in the direction of operation of the button. The lip 5 forms at its top an abutment 7 and an edge-shaped abutment 8 the object of which will be more closely described hereinafter. The abutment 8 can either have a more or less sharp edge-form or be rounded. The lip 6 is provided with an edge-shaped abutment 9 of similar nature as the abutment 8 and provided with a locking abutment 10. The abutments 7 to 10 cooperate with a locking member 11 the right hand end of

which is free whereas its left hand end is rotatably mounted at 12 on the oscillating end of a thermostat member 13. The thermostat member is fixed by its right hand end to a standard 14. The locking member 11 is held to bear against the abutments 8 and/or 9 respectively by means of a spring 15 fixed to the standard 16. The button 3 is further provided with a contact piece 17 cooperating with a spring contact 18 mounted on the standard 19. Further the button 3 is provided with a contact blade 20 cooperating with two resilient contact blades 21, 22.

To the one pole 23 of the electric supply line 15 there is connected a heating winding 24 mounted on the thermostat member the other terminal of said winding being connected to the contact piece 18. According to Fig. 1 the main switch of the device formed by the parts 20 to 22 governs the connection between the load 25, such as one or more incandescent lamps, and the other pole 26 of the electric line.

It is assumed that the button 3 is made of electrically conducting material, at least in its lower portion, or from insulating material in which latter case the contact pieces 17 and 20 must be electrically interconnected.

The device operates in the following manner. In their starting position the parts take up the positions shown in Figs. 1 and 2 in which the switch 20 to 22 is open and the contacts 17 and 18 separated so that no current can pass the load 25 or the heating winding 24. When it is desired to connect the load 25 into circuit for a limited period the button 3 is pushed down to its lowermost position in which the locking member 11 snaps in over the abutment 7 and is brought to bear elastically against the abutment 9 according to Fig. 4. In this way the button 3 is retained in its pushed-down position in which the switch 20 to 22 and the contacts 17 and 18 are closed. Then the current passes two paths, i. e. the one through the load 25 and contact blades 20 to 22 and the other through the heating winding 24, the contacts 17, 18 and the blades 20, 21 connected to the opposite pole 26. The thermostat member begins to be heated and bends itself successively to the position shown in Fig. 5 while rotating the locking member about the axis of rotation defined by the abutment 9. Then the abutment 7 is released and under the action of the spring 4 the button 3 is raised so far that instead the abutment 10 comes into locking engagement with the locking member 11. The upward step of the button corresponds apparently

to the mutual spacing or difference in level, counted in the direction of operation, between the abutments 7 and 10 and is sufficient to separate the contacts 17 and 18 from one another whereas the blade 20 still remains in conducting contact with the blades 21 and 22. While the load 25 remains in circuit the heating winding 24 is disconnected and the thermostat member cools down and starts to straighten itself again until the position according to Fig. 6 is reached while rotating the locking member 11 about the abutment 8. In this way the abutment 10 is released and the button 3 is raised on account of the spring 4 to the position shown in Fig. 2. When the cooling of the thermostat member has proceeded down to normal temperature the parts 11 and 13 take up the positions shown in Fig. 1 so that the device is restored to its starting position.

Apparently the switching procedure can be repeated at any time both in the position shown in Fig. 1 as in an intermediate position between those indicated in Figs. 1 and 6. As will be understood from the above the locking member 11 will be brought to rotate in its reciprocating shifting movement about two different axes of rotation, i. e., the axes defined by the abutments 8 and 9 which are parallel with the direction of operation of the button 3.

In the embodiment shown in Figs. 1 to 3 the thermostat member is shown as an immediate carrier of the locking member. Of course, there is no objection to arrange the parts according to Fig. 5a in which a thermostat member 27 of suitable design actuates the locking member 30 through the intermedium of a connecting means, such as a link 28 with an elastic adjustable setting device 29. The important feature is that the locking member is held on a definite level in regard to the one movable part and movable in a plane perpendicular to the direction of operation under the control of a spring power 32 so as to swing about the point 31 of application of the connecting means 28 and bear elastically against one of the abutments, such as 8 or 33.

During its rotation about one of its axes of rotation the locking member is retained by the corresponding locking abutment only within a definite angular field and as soon as this field has been passed in a definite direction the locking member allows the corresponding movable part to snap-forward one step.

When comparing the positions shown in Figs. 1 and 6 it is seen that the locking member passes through its angular position shown in Fig. 6 to a complete release of the two movable parts from one another while the temperature of the thermostat member is higher than a normal temperature when there is no operation. As the cooling time of the thermostat is primarily decisive for the release period of the device such a period can be adjusted by setting the temperature prevailing in the moment of release according to Fig. 6. This can be achieved according to the present invention by making the thermostat member so adjustable in relation to the locking member and the abutment that the starting angle A, Fig. 1, of the locking member can be varied.

What is claimed is:

1. A locking device for temporarily interlocking a pair of relatively movable members comprising a plurality of locking abutments associated with one of said members and staggered in the direction of movement to permit stepwise

relative movement of the members, means tending to move the members relative to one another, and a locking member adapted to perform a rotary movement about different axes of rotation so as to engage said abutments successively and thereby permit the members to move relative to one another in a stepwise fashion.

2. A locking device for temporarily interlocking a pair of relatively movable members comprising a plurality of locking abutments associated with one of said members and staggered in the direction of movement to permit stepwise relative movement of the members, means tending to move the members relative to one another, 10 a thermostat, an electric resistance adapted to heat said thermostat, a locking member actuated by movement of said thermostat and adapted to perform a rotary movement about different axes of rotation under the control thereof so as to engage said abutments successively and thereby permit the members to move relative to one another in a stepwise fashion, and a pair of electric contacts carried by said members for energizing the circuit leading to said electrical resistance.

3. A delayed action switch comprising a pair of relatively movable members, a plurality of locking abutments associated with one of said members and staggered in the direction of movement to permit stepwise relative movement of the members, means tending to move said members relative to one another, a thermostat, an electric resistance adapted to heat said thermostat, a locking member actuated by movement of 30 said thermostat and adapted to perform a rotary movement about different axes of rotation under the control thereof so as to engage said abutments successively and thereby permit the members to move relative to one another in a stepwise fashion, a pair of electric contacts carried by said members for energizing the circuit leading to said electrical resistance, and a second pair of electric contacts carried by said members for energizing a circuit controlled by said switch.

4. A locking device for temporarily interlocking a pair of relatively movable members according to claim 1 characterized by the fact that the axes of rotation of the locking member are defined by narrow abutments extending parallel to the direction of movement of the relatively movable members against which the locking member bears elastically.

5. A locking device for temporarily interlocking a pair of relatively movable members according to claim 1 characterized by the fact that the axes of rotation of the locking member are defined by narrow abutments extending parallel to the direction of movement of the relatively movable members against which the locking member bears elastically and that the locking abutments are so arranged with respect to the abutments against which the locking member bears that in rotation of the locking member about its axes of rotation it engages the abutment on the corresponding movable member only within a definite angular field and in its rotation beyond such field permits the corresponding movable member to move one step in its direction of movement.

6. A locking device for temporarily interlocking a pair of relatively movable members comprising a plurality of locking abutments associated with one of said members and staggered in the direction of movement to permit stepwise

relative movement of the members, means tending to move the members relative to one another, a thermostat, an electric resistance adapted to heat said thermostat, a locking member actuated by movement of said thermostat and adapted to perform a rotary movement about different axes of rotation under the control thereof so as to engage said abutments successively and thereby permit the members to move relative to one another in a stepwise fashion, the thermostat being so arranged in relation to the locking member as to actuate the locking member to completely release the relatively movable members while the temperature of the thermostat is above its normal temperature when inoperative, and a pair of electric contacts carried by said members for energizing the circuit leading to said electrical resistance.

7. A locking device for temporarily interlocking a pair of relatively movable members comprising a plurality of locking abutments associated with one of said members and staggered in the direction of movement to permit stepwise relative movement of the members, means tending to move the members relative to one another, a thermostat, an electric resistance adapted to heat said thermostat, a locking member actuated by movement of said thermostat and adapted to perform a rotary movement about different axes of rotation under the control thereof so as to engage said abutments successively and thereby permit the members to move relative to one another in a stepwise fashion, the thermostat being adjusted with respect to the locking member and the locking abutments associated with the relatively movable members so that the initial angular position of the locking member can be varied, and a pair of electric contacts carried by said members for energizing the circuit leading to said electrical resistance.

8. A locking device for temporarily interlock-

- ing a pair of relatively movable members comprising a plurality of locking abutments associated with one of said members and staggered in the direction of movement to permit stepwise relative movement of the members, means tending to move the members relative to one another, a thermostat fixedly mounted at one end and free at the other, an electric resistance adapted to heat said thermostat, a locking member rotatably connected to the thermostat adjacent its free end actuated by movement of said thermostat and adapted to perform a rotary movement about different axes of rotation under the control thereof so as to engage said abutments successively and thereby permit the members to move relative to one another in a stepwise fashion, and a pair of electric contacts carried by said members for energizing the circuit leading to said electrical resistance.
9. A locking device for temporarily interlocking a pair of relatively movable members comprising a plurality of locking abutments associated with one of said members and staggered in the direction of movement to permit stepwise relative movement of the members, means tending to move the members relative to one another, a thermostat fixedly mounted at one end and free at the other, an electric resistance adapted to heat said thermostat, a locking member rotatably connected to the thermostat through a linkage actuated by movement of said thermostat and adapted to perform a rotary movement about different axes of rotation under the control thereof so as to engage said abutments successively and thereby permit the members to move relative to one another in a stepwise fashion, and a pair of electric contacts carried by said members for energizing the circuit leading to said electrical resistance.
